CORE CATCHER

Alfred C. Catland, Alhambra, and Philip C. Efronson, Whittier, Calif., assignors to Globe Oil Tools Company, Los Nietos, Calif., a corporation of California

Application October 13, 1936, Serial No.105,370

10 Claims. (Cl. 255—72)

This invention relates to well drilling tools and relates more particularly to a core catcher for use in a rotary core drill. A general object of the invention is to provide a practical, effective and very dependable core catcher.

Another object of the invention is to provide a core catcher embodying slips for gripping the core and pivoted dogs for assisting in gripping the core and for relieving the strain on the slip carrying springs when the core catcher is actuated.

Another object of this invention is to provide a core catcher embodying a slip ring or body presenting tapered surfaces for actuating the slips and carrying pivoted core gripping dogs that operate to hold the body against turning and undesirable movement, thereby reducing the strains on the springs which carry the slips.

Another object of the invention is to provide a core catcher of the character mentioned in which the provision or inclusion of the core gripping dogs does not complicate the construction or require the enlargement of the core catcher body.

Another object of this invention is to provide a core catcher of the character mentioned in which the pivoted dogs are positive and dependable in gripping and supporting the core and are capable of dependably gripping cores of various earth formations.

A further object of the invention is to provide a core catcher of the character mentioned that does not foul the core, score the core, or otherwise injure the core during the drilling operation.

The various objects and features of our invention will be fully understood from the following detailed description of a typical preferred form and application of the invention, throughout which description reference is made to the accompanying drawings, in which:

Fig. 1 is a vertical detailed sectional view of the lower portion of a core drill illustrating the core catcher of the present invention in the operative position in the drill. Fig. 2 is a transverse detailed sectional view taken as indicated by line 2—2 on Fig. 1. Fig. 3 is a fragmentary, enlarged, vertical, detailed sectional view of the core catcher within the drill and Fig. 4 is a transverse detailed sectional view of the core catcher taken as indicated by line 4—4 on Fig. 3.

The core catcher of the present invention is suited for use in core drills of various types and constructions. In the drawings we have illustrated the core catcher arranged in a rotary rock

5 derstood that the invention is not to be construed as limited or restricted to the specific form or application of the invention illustrated.

The core drill illustrated in the drawings includes an outer barrel 10 adapted to be connected with the lower end of a rotary drilling string. A special sub 11 is threaded on the lower end of the outer barrel 10. The sub 11 extends a considerable distance below the outer barrel 10 and has a relatively large internal diameter. A bit 10 head 12 is screw threaded on the lower end of the sub 11. Circumferentially spaced recesses 13 and 14 are provided in the lower end of the bit head 12 to receive roller cutters 15 and 16, respectively. The roller cutters 15 and 16 are 15 rotatably supported on pins 15^a and 16^a extending across the recesses 13 and 14. The central vertical openings 17 in the tubular bit head 12 is adapted to freely receive the core cut or formed by the cutters 15 and 16. An annular recess 18 20 is provided within the bit head 12.

The core drill further includes a tube or sleeve 19 which seats downwardly in the recess 18 of the head 12 and which extends upwardly through the sub 11. The sleeve 19 is spaced from 25 the interior of the sub 11 leaving an annular fluid passage 20. Ports 21 in the bit head 12 conduct the circulation fluid downwardly from the passage 20 to the recesses 13 and 14 to flush the cutters 15 and 16. A flat annular upwardly 30 facing shoulder 22 is provided on the interior of the sleeve 19. A tapered annular shoulder 23 occurs on the interior of the sleeve 19 above the shoulder 22. The sleeve 19 is tapered or flared outwardly adjacent its upper end. The core 35 drill includes an inner barrel 24 arranged longitudinally in the outer barrel 10 to receive the core. A bearing collar 25 is fixed to the lower end of the inner barrel 24. A shoulder 26 on the collar 25 is adapted to bear downwardly 40 against the upper end of the sleeve 19 and the collar carries a hardened bearing ring 27 for bearing upwardly against a shoulder 28 on the interior of the sub 11. The inner barrel 24, supported as just described, is free to float, that is, 45 it may turn or remain stationary at will. The sleeve 19 is also floating so that it may remain stationary during rotation of the drill. Ports 30 are provided in the collar 25 to connect the passage 20 with the annular circulation space 31 50 between the two barrels 10 and 24.

The core catcher of the present invention includes, generally, what we will term a body 32, pivoted core gripping dogs 33 on the body 32, a ring 34 below the body 32, slips 35 connected 55

with the ring 34 and operable through cooperation with the body 32, and springs 36 on the ring 34 for cooperating with the core to control the slips 35.

- 5 The body 32 is provided to carry the dogs 33 and to present tapered abutments for actuating the slips 35. The body 32 is a tubular element arranged within the sleeve 19 of the drill. In the preferred construction the body 32 is sectional comprising two telescopically arranged rings A and B. The ring A forms the upper portion of the body 32 and has a flat upper end adapted to cooperate with the lower end of the collar 25 to limit the upward movement of the body 32. The ring A fits in the sleeve 19 for free longitudinal and turning movement. The upper portion of the ring A may be flared outwardly to fit within the correspondingly flared portion of the sleeve 19. An internal annular recess 37 extends upwardly in the ring A from its lower end. The recess 37 may have a flat upper wall and a cylindrically curved side wall. Notches or openings 38 are provided in the lower end of the body ring A. The openings 38 are circumferentially spaced and have communication with the recess 37. The upper portion of the body ring A is shaped or formed to receive the slips 35. Circumferentially spaced longitudinal slots 39 are provided in the upper portion 30 of the body ring A to receive the slips 35. The slots 39 extend downwardly from the upper end of the body ring A to the recess 37. The side walls of the slots 39 may be flat and parallel while the bottom or inner walls 40 of the slots 35 are inclined downwardly and inwardly relative to the vertical axis of the drill. The slot walls 40 form inclined abutments for the slips 35.
- 30 The body ring B nests in the lower portion of the ring A fitting upwardly in the recess 37. The ring B is generally cylindrical both inside and outside and has flat ends. The lower end of the body ring B is adapted to cooperate with the shoulder 22 to limit the downward movement of the body 32. The body 32 is proportioned to have limited vertical or longitudinal movement in the sleeve 19. An annular external groove 41 is provided in the body ring B. The outer side of the groove 41 is closed by the lower wall portion of the ring A. Rivets 42 are provided in vertically and circumferentially spaced openings 50 in the telescoping portions of the rings A and B to connect the rings. The lower rivets 42 may pass radially through the groove 41. Circumferentially spaced openings 43 are provided in the wall of the ring B. The openings 43 are vertically elongate and extend downwardly from the upper end of the ring B. The parts are related so that the openings 43 are vertically aligned with the openings 38 and their lower ends communicate with the openings 38. The 55 communicating openings 38 and 43 lie in vertical planes spaced between the vertical planes of the slots 39. The upper inner corner of the body ring B may be bevelled off to be flush with the inclined walls 40 of the slots 39. The lower end 60 of the body ring A clears the inclined shoulder 23 when the lower end of the ring B is in cooperation with the shoulder 22. The opening through the tubular or annular body 32 freely receives or passes the core.
- 65 70 The dogs 33 are operable to grip the core to assist in breaking it free from the formation and to assist in retaining it in the drill. The dogs 33 also operate to prevent undesirable relative movement between the body 32 and the ring 34 thus relieving the strains on the spring mem-

bers connecting the slips 35 with the ring 34. The dogs 33 are solid tooth-like parts having pointed or tapered active ends to bite into the core. In the structure illustrated the dogs 33 are pivotally mounted in the openings 43 in the body ring B to have their outer portions project into the openings 38 in the body ring A. Pivot pins 44 pass through openings in the dogs 33 and have their opposite ends supported in the groove 41 to pivotally support the dogs. Notches 45 are provided in the outer portions of the dogs 33 to receive torsional springs or spring wires 46. The spring wires 46 each have an end bearing on a wall of the recess 37 and an end bearing on a dog 33 to urge the dog against the core. Cams 47 may be provided on the projecting outer portions of the dogs 33 to cooperate with the shoulder 23 and assist in pivoting the dogs downwardly and inwardly into the core when the core catcher is actuated. The lower walls of the openings 43 form abutments to limit the downward pivoting of the dogs 33 and to assist in supporting the load carried by the dogs. Fig. 1 illustrates the dogs 33 in cooperation with the lower walls of the openings 43. The active or biting ends of the dogs 33 are received in the openings 43 when the core extends through the body 32 so that the dogs do not interfere with the core.

In accordance with the invention the dogs 33 are of different lengths. Certain of the dogs 33 are relatively long to bite into soft and undersized cores, certain of the dogs are of medium length to bite into medium hard cores and certain of the dogs are relatively short to grip hard cores or rock cores. The dogs 33 are preferably equally spaced about the interior of the body 32 as illustrated throughout the drawings.

The ring 34 may be a simple integral member and is arranged in the sleeve 19 below the body 32. The ring 34 is free to turn and move longitudinally in the sleeve 19 and is proportioned to freely pass or receive the core. The lower end of the body 32 limits the upward movement of the ring 34.

The slips 35 are wedge-like gripping parts operable in the slots 39. The back sides or surfaces 47 of the slips 35 are inclined downwardly and inwardly to slidably cooperate with the walls 40 of the slots 39. The active inner surfaces of the slips 35 are curved to conform, generally, to the core and have horizontal wickers or teeth 48 for gripping the core. The slips 35 are connected with the free ring 34 to operate in unison and to be controlled by cooperation of springs 36 with the core. Springs 49 connect the slips 35 with the ring 34. The springs 49 are secured to the interior of the ring 34 by rivets 50. The upper portions of the springs 49 are secured to the back sides of the slips 35 by rivets 51 or the like. The springs 49 are preferably recessed or countersunk in the inclined surfaces 47 of the slips. The springs 49 extend vertically through the body ring B and the slots 39. The parts are related so that the springs 49 are spaced between the spaced dogs 33.

The springs 36 are provided to have movement resisting cooperation with the core when the drill is raised so that the slips 35 are actuated inwardly by the upwardly moving inclined surfaces or walls 40. The springs 36 are in the nature of leaf springs or spring arms secured to the ring 34 to project upwardly and inwardly from its interior. In practice the springs 36 may be secured to the ring 34 by the rivets 50. The upper portions of the springs 36 may be bent inwardly

to more effectively engage the core. The springs 36 are sufficiently flexible to yield or flex outwardly when the core is received in the drill so that they do not interfere with or injure the core. 5
3. As the body 32 and the ring 34 may remain non-rotatable during the drilling operation the springs 36 do not turn during the drilling and, therefore, do not score the core.

During the drilling operation the cutters 15 and 16 make an annular cut in the earth formation leaving a core which is received in the drill. The core is adapted to extend upwardly through the body 32 to be received in the inner barrel 24. The engagement of the springs 36 with the core holds the ring 34 in a position where the slips 35 are retracted in the upper portions of the slots 39. The springs 36 engaging the core also resist or prevent turning of the ring 34 and the slips 35 connected with the ring. The spring urged dogs 33 engage the core to resist turning of the body 32 relative to the core. Thus the ring 34, the slips 35 and the body 32 may remain non-rotatable during the drilling operation. The dogs 33 urged against the core by the spring wires 46 prevent or tend to prevent turning of the body 32 so that the springs 49 are subjected to little or no torsional stress.

After a core of sufficient length has been cut the drill is raised to actuate the core catcher. 30 When the drill is raised the engagement of the shoulder 22 with the lower end of the body ring B causes the body 32 to move upwardly with the drill. The springs 36 bearing against the core hold the ring 34 against upward movement and hold the slips 35 against upward movement. Accordingly, upward movement of the body 32 results in active cooperation of the slot walls 40 with the rear surfaces 47 of the slips 35. The inclined walls 40 cooperating with the surfaces 47 force the slips 35 inwardly into gripping engagement with the core. During this actuation of the slips 35 the spring urged dogs 33 individually pivot downwardly and inwardly into biting engagement with the core. In practice the vertical movement of the body 32 necessary to actuate the slips 35 effects the proper actuation of the pivoted dogs 33. During the pivotal movement of the dogs 33 from substantially vertical positions to the positions illustrated in Fig. 1 of the drawings the body 32 may be moved vertically to effect the complete inward actuation of the slips 35. Thus the slips 35 and the dogs 33 simultaneously obtain firm gripping engagement with the core. Further upward movement of the drill results in breaking free of the core from the earth formation. The core is recovered from the well in the drill. The slips 35 and the dogs 33 serve to dependably support the core in the drill as the drill is withdrawn from the well.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. A core catcher for use in a tubular well drill including, an annular body for arrangement in the drill to move vertically therewith, a free ring below the body, slips connected with the ring and actuated into gripping engagement with the core by cooperation with the body, and pivoted core gripping dogs on the body.

2. A core catcher for use in a tubular well drill

including, an annular body for arrangement in the drill to move vertically therewith, a free ring below the body, slips connected with the ring and actuated into gripping engagement with the core by cooperation with the body, means on the ring 5 cooperable with the core to resist movement of the ring, and pivoted dogs on the body cooperable with the core to prevent undesirable movement of the body and to grip the core.

3. A core catcher for use in a tubular well drill including, an annular body for arrangement in the drill to move vertically therewith, a free ring below the body, slips connected with the ring and actuated into gripping engagement with the core by cooperation with the body, and spring urged 15 dogs on the body engaging the core to prevent relative turning between the body and ring.

4. A core catcher for use in a tubular well drill including, an annular body for arrangement in the drill to move vertically therewith, a free ring 20 below the body, slips connected with the ring and actuated into gripping engagement with the core by cooperation with the body, means on the ring for engaging the core to resist turning of the ring, and means on the body for engaging 25 the core to resist turning of the body.

5. A core catcher for use in a tubular well drill including, an annular body for arrangement in the drill to move vertically therewith, a free ring 30 below the body, slips connected with the ring and actuated into gripping engagement with the core by cooperation with the body, means on the ring for engaging the core to resist turning of the ring, and means on the body for engaging the 35 core to resist turning of the body, the last mentioned means including dogs pivoted on the body, and means urging the dogs against the core.

6. A core catcher for use in a rotary core drill including, a floating tubular body in the drill capable of free turning and limited vertical movement, the body having inclined slots, a floating ring below the body, slips in the slots operable 40 inwardly by their inclined walls, spring members connecting the slips with the ring to move therewith, means on the ring engageable with the 45 core to resist movement of the ring, and spring urged dogs on the body for gripping the core.

7. A core catcher for use in a rotary core drill including, a floating tubular body in the drill capable of free turning and limited vertical movement, the body having inclined slots, a floating ring below the body, slips in the slots operable inwardly by their inclined walls, spring members connecting the slips with the ring to move therewith, means on the ring engageable with the core to resist movement of the ring, and spring urged dogs of different lengths on the body for gripping the core.

8. A core catcher for use in a rotary core drill including, a floating tubular body in the drill 60 capable of free turning and limited vertical movement, the body having circumferentially spaced inclined slots, a floating ring below the body, slips in the slots operable inwardly by their inclined walls, spring members connecting the slips with the ring to move therewith, means on the ring engageable with the core to resist movement of the ring, and pivoted dogs on the body spaced between the spring members and operable to grip the core.

9. A core catcher for use in a rotary core drill including, a floating tubular body in the drill capable of free turning and limited vertical movement, the body having circumferentially spaced inclined slots, a floating ring below the body,

slips in the slots operable inwardly by their inclined walls, spring members connecting the slips with the ring to move therewith, means on the ring engageable with the core to resist movement of the ring, pivoted dogs on the body spaced between the spring members and operable to grip the core, and means yieldingly urging the dogs against the core.

10. A core catcher for use in the core receiving opening of a core drill comprising, a tubular

body arranged in the opening to move vertically with the drill, a shiftable member in the opening below the body, slips connected with the member and actuated into gripping engagement with the core by cooperation with the body upon upward movement of the body with the drill, and pivoted core gripping dogs on the member. 5
